C. SPIRO.
TYPEBAR ACTION.
APPLICATION FILED JAN. 4, 1919.

UNITED STATES PATENT OFFICE.

CHARLES SPIRO, OF NEW YORK, N. Y., ASSIGNOR TO GOURLAND TYPEWRITER CORPORATION, OF NEW YORK, N. Y., A CORPORATION OF NEW YORK.

TYPEBAR-ACTION.

1,391,020.

Specification of Letters Patent. Patented Sept. 20, 1921.

Application filed January 4, 1919. Serial No. 269,604.

To all whom it may concern:

Be it known that I, CHARLES SPIRO, citizen of the United States, residing at New York, in the county of New York and State 5 of New York, have invented certain new and useful Improvements in Typebar-Actions, of which the following is a specification.

This invention relates to a typebar action for typewriting machines, and particularly 10 to a construction wherein the operative parts are closely nested to produce a compact arrangement occupying the minimum of space.

The invention has for an object to provide 15 a novel and improved construction and arrangement of the key lever, type bar and intermediate connecting sublever, with the pivot of the sublever disposed in a plane beneath the pivot of the key lever so as to permit the disposition of the typebar immediately above said key lever.

Another and further object of the invention 20 is to provide an improved construction of key lever having a depressed portion at its upper surface to receive the typebar, and 25 means for connection with a sublever pivoted in a plane beneath the pivot of the key lever.

Other and further objects and advantages 30 of the invention will be hereinafter set forth and the novel features thereof defined by the appended claims.

In the drawing—

Figure 1 is a transverse vertical section at 35 the center of the machine showing the assembled relation of the parts.

Fig. 2 is an elevation of one of the key levers.

Fig. 3 is a detail vertical section at a right 40 angle to Fig. 1 and at one side of the center of the sector; and

Fig. 4 is an elevation of one of the sub-levers.

Like numerals refer to like parts in the several figures of the drawing.

45 The numeral 10 designates the frame of a typewriting machine which may be of any desired character or configuration and is provided with the usual feet 11 by which it is raised above the support upon which the machine rests. The rear wall 12 is provided 50 at its lower portion with a plate 13 spaced therefrom and extending downward parallel

to the wall to provide at its free edge 14 a pivotal bearing or fulcrum for the inner end of the key lever 15.

This lever involves a novel construction for its attachment to the sublever 16 and to permit the close nesting of the type-bar 17 so as to provide a compact construction occupying the minimum of space. The key 60 lever 15 is provided at its outer end with the usual finger piece 18 at the keyboard of the machine, and has an upwardly inclined portion 19 extending rearwardly therefrom and terminating in a shoulder 20 connecting 65 with an inclined depressed portion 21 forming a space to receive the typebar when at rest. When in this position the head 22 of the typebar is in substantially the same horizontal plane as the finger piece of the key 70 lever.

The depressed portion 21 of the key lever is provided at its inner end with a raised shoulder 23 from which a horizontal portion 24 extends to an elevated spring seat 25. At 75 the rear of this seat the key lever is formed with the pivoting end 26 having the socket 27 to engage the edge 14 of the bearing plate 13. Disposed within the seat 25 and surrounding the lug 28 therein, is the lifting spring 29 which rests at its opposite end upon a fixed support 30 and surrounds a lug 31 extending upward therefrom. These parts are duplicated for each of the several key levers.

80 The sublevers 16 are pivotally mounted in a cross bar 32 extending between the opposite sides of the machine frame beneath the plane of the key lever pivots and intermediate the length of said key levers. This 85 cross bar is provided with a series of vertical slots 33 to receive the several sub levers and also with a longitudinal groove 34 within which the pivoting rod 35 for the sub levers extending across the machine is disposed. The sublevers are of a substantially bellcrank type and comprise a pivoting portion 36 from which a horizontal slotted connecting arm 37 extends and is connected to the key lever at a point below the pivot 90 thereof by any desired means, such as a pin 38 extending laterally from the key lever. This provides a pin and slot connection 95 between the sub lever and key lever

giving a sliding pivotal connection at that point which provides an increased leverage during the downward stroke of the key.

Extending upward from the pivotal portion 36 of the sublever is a connecting arm 39, which may be of any desired length and disposed at the proper angle necessary to provide connection with the type bars in the ascending arc of the sector 43. This arm 10 39 is provided at its upper end with the usual connecting pin 40 disposed in the actuating groove 41 at the inner end of the type bar 17. The type bar is fulcrumed at one end of this groove by engaging the pivot 15 42 carried by the type bar sector 43 as customary in this art. The arms 39 of the several sublevers at each side of the center of the sector are deflected laterally at different degrees as usual to accommodate them to the 20 positions of the type bars in the ascending arc of the sector.

This sector carries the ordinary universal bail 44, which is actuated by the portion 45 of the type bar to impart thereto a rearward 25 sliding movement. The bail is connected to the escapement dogs 47 by a swinging link 46 pivoted thereto and to the tail 48 depending from the dogs. These dogs are supported from the carriage frame 49 in 30 the usual manner and move therewith in the vertical shifting of the carriage to bring the platen 50 into position for either upper or lower case writing. The link connection permits the bail to maintain accurate and 35 constant relation with the escapement mechanism in either shifted position of the carriage.

The head 22 of the type bars 17 rests upon the usual support 51 when in inactive position, and in the present construction this support is disposed in the depressed nesting space above the key levers.

The operation of the invention will be apparent from the foregoing description and 45 it will be seen that the disposition of the sub lever and its connection with the key lever and type bar provide for increasing leverage during the downward stroke of the key lever and an accelerated movement of 50 the type bar in its travel toward the platen, thus securing in a closely nested or compact construction the important advantages of this character of type bar action. It will be noted that these desirable results are 55 secured by disposing the pivot of the sub lever in a plane below the pivot of the key lever, and are facilitated by providing the connection between these levers below the fulcrum of the key lever.

60 This invention also presents a special novel construction of key lever providing for the nesting of the type bar immediately above its upper surface, and also with means for mounting and connecting the lifting 65 spring which requires the least possible

space to secure the necessary action, and leaves the space above the key levers at the rear of the machine free for the disposition of other mechanism. This is an important contributory feature in the construction of 70 a low, compact and light weight typewriter.

While the details of construction of a number of the parts have been specifically described, still the invention is not confined thereto as defined by the following claims. 75

What I claim is:—

1. A type bar action comprising a key lever pivoted adjacent the rear of the typewriter, a type bar pivotally mounted at a point above said key lever, a bell crank lever 80 swinging about a fixed pivot positioned below said key lever, a pin and slot connection between said key lever and one arm of said bell crank lever, and a pin and slot connection between the other arm of said bell crank 85 lever and said type bar, whereby the height of said type bar action is materially decreased.

2. A typebar action comprising a key lever pivoted adjacent the rear of a typewriter, a 90 typebar pivotally mounted at a point above said key lever, and an angular lever swinging about a fixed pivot positioned below said key lever and directly engaging said typebar and also said key lever intermediate the 95 ends thereof, whereby the height of said typebar action is materially reduced.

3. A typebar action comprising a key lever pivoted adjacent the rear of a typewriter, a typebar pivotally mounted at a point above 100 said key lever, an angular lever swinging about a fixed pivot positioned below said key lever and directly engaging said typebar and also said key lever intermediate the ends thereof, and a restoring spring for said key 105 lever disposed above the pivot of said angular lever.

4. A typebar action comprising a key lever pivoted adjacent the rear of a typewriter and having a raised spring seat, a typebar 110 pivotally mounted at a point above said key lever, an angular lever swinging about a fixed pivot positioned below said key lever and directly engaging said typebar and also said key lever intermediate the ends thereof, 115 and a restoring spring for said key lever disposed above the pivot of said angular lever and entering said seat.

5. In a typebar action, a pivoted key lever provided with a depressed portion intermediate its ends, a pivoted type bar arranged to be disposed within said portion when at rest, and a connecting sub lever pivoted beneath the key lever at the rear of said depressed portion adjacent the typebar pivot 120 125 and directly connected to said key lever at the inner end of said depressed portion.

6. In a typebar action, a key lever pivoted at its inner end and provided with a depressed portion intermediate its ends and a 130

raised spring seat adjacent its pivotal point, a lifting spring disposed within said seat, a pivoted type bar disposed to nest in the depressed portion of the key lever, and a 5 sub lever pivoted beneath the key lever adjacent the typebar pivot and directly connected to said key lever and type bar.

7. A key lever having an upwardly inclined portion extending rearwardly from 10 its key board end and terminating in a shoulder, a depressed portion extending rearward from said shoulder to a raised horizontal portion and provided with a sub lever connection at the inner end of the depressed portion, a raised spring seat formed in said horizontal portion, and a pivoting end extended from said seat.

8. In a type bar action, a pivoted key lever

provided with a depressed portion intermediate its ends, a type bar arranged to nest in 20 said depression when at rest, a second lever pivoted below said key lever and operatively engaging said type bar, and a connection from said key lever to said second lever.

9. In a typebar action, a pivoted typebar, 25 a sub lever pivoted below the typebar and directly engaging the same, and a key lever having its rear pivoted portion located above the sub lever fulcrum and its body provided with a lost motion connection with the sub 30 lever and having its forward key supporting portion elevated for its stroke movement above the horizontal plane of the sub lever fulcrum.

In testimony whereof I affix my signature. 35
CHARLES SPIRO.
